UNITED STATES PATENT OFFICE.

SHERMAN H. PAXTON, OF ST. PAUL, MINNESOTA.

PRINTING DEVICE.

1,372,085.

Specification of Letters Patent.

Patented Mar. 22, 1921.

Application filed May 29, 1919. Serial No. 300,674.

To all whom it may concern:

Be it known that I, SHERMAN H. PAXTON, a citizen of the United States, residing at St. Paul, in the county of Ramsey and State 5 of Minnesota, have invented new and useful Improvements in Printing Devices, of which the following is a specification.

My invention relates to improvements in printing devices, adapted particularly for 10 use on wrapping paper, sacks, cartons in the flat and other wrappers and containers of merchandise.

The object of my invention is to produce a printing device which will operate efficiently and automatically upon an ordinary roll paper dispensing rack and also serve as 15 an effective manually operative printing press.

A further object is to organize such a 20 printing mechanism so that the printing roll may rotate in one direction only when attached to a rack and reciprocate when operated by hand.

A further object is to adapt such a device 25 to print upon irregular surfaces of an ordinary roll of paper.

In the drawings Figure 1 is a perspective view of a roll paper rack of ordinary construction, with my printing press attached thereto. Fig. 2 is a plan of the clamp and hanger for attaching the press to the 30 rack. Fig. 3 is an elevation of the same. Fig. 4 is a perspective view of the press with a handle for manual operation. Fig. 5 is a 35 view of the printing roller with a portion thereof shown in sections on the line 5—5 of Fig. 4. Fig. 6 is a fragmentary detail of parts shown in Fig. 5, with the detent out of engagement.

Referring to the drawings, A indicates a 40 roll paper rack of ordinary construction, B the clamp and hanger for attaching the press to the rack, C the press proper and D a handle for manually operating the press.

The clamp B consists of a body portion 10 adapted to be applied to the top of the frame of the rack A by means of the clamping ears 11 and thumb screw 12. The ears 11 are turned down substantially at right angles 45 to the body 10, their vertical edges 13 forming the clamping contacts for the frame. A U-shaped hanger 14 is journaled between the inner surfaces of the ears 11 upon the rod 15, and a coiled spring 16 is mounted upon 50 said rod 15 with its looped center 17 bearing upon the upper surface of the body portion

10 of the clamp, while the projecting ends 18 are held in grooves in the cross bar 19 of the hanger. Upon the lower surface of this bar 19 of the hanger a projection 20 is 60 formed with a threaded pintle 21 to furnish a mounting for the press C hereafter described.

The press C consists of a heavy metallic casing 22 in which are journaled an inking 65 roller 23, a distributing roller 24 and a printing roller 25. The inking and distributing rollers 23 and 24 are mounted and coöperate with the printing roller 25 in the usual manner.

A cavity 26 is formed in one end of the printing roller 25, and in this cavity a coiled 70 spring 27 is placed about the axial pin 28 which is rigidly attached at its inner end to the roller 25. The inner end of said spring 75 27 is also fixed in the roller 25 while its outer end is fixed in a disk 29, which is normally free to rotate upon said pin 28, with its outer surface adjacent to the inner surface of the side 22^a of the casing 22. When my 80 device is used for automatic work upon the paper rack A this disk 29 revolves freely with the printing roller 25. I have, however, provided means for causing the spring 27 to return the roller to initial position after 85 each manual printing stroke by the following means: A nipple 30 is arranged in the side 22^a of the casing 22, in which a detent 31, having a cross-head 32, is mounted in a spiral spring 33, held between the internal 90 flange 30^a in the nipple and the disk 31^a fixed on the detent, to press said detent inwardly, and the disk 29 is perforated at 34 to receive the inner end of the detent when it is allowed to respond to the tension of said 95 spring. When the detent 31 is depressed by the spring 33 the disk 29 is connected to the casing and held against revolution by the registration of the pin in perforation 34 (see Fig. 5) so that each printing revolution 100 of the roller 25 is against the action of the spring 27, but when the pressure of a manual printing stroke is released the roller 25 is returned to initial position by said spring 27.

When it is desired to have the printing 105 roller 25 revolve continuously in one direction, as in automatic printing upon the paper roll, the detent 31 is drawn out by means of cross-head 32 and turned so that said cross-head is allowed to rest in the grooves 110 35 in the outer end of the nipple 30 (see Fig. 6), and when it is desired to connect the

disk 29 to the casing 22 the cross-head 32 is turned so that the tension of the spring 33 may draw it into the slots 36 formed in the nipple 30 (see Fig. 4), thereby permitting 5 tension of the spring 33 to press the inner end of the detent 31 against the outer surface of the disk 29, which may then be turned manually to permit the detent to penetrate the perforation 34 in the disk 29 and thereby 10 hold said disk against rotation. When the detent is in this position it will be noted that the pin 44 (which attaches the inner end of the spring 27 to the roller) and the screw 45 (which attaches the other end of 15 said spring to the disk 29) are extended to impinge against each other after a predetermined rotation of the roller 25, to limit its movement when the spring 27 is operative (see Fig. 5).

20 To facilitate attaching and removing the printing press C from the clamp B I have formed at the base of one of the legs of the hanger 14 a notch 37, and in one of the ears 11 a perforation 38 (see Figs. 2 and 3), and 25 when it is desired to either attach or remove the press the hanger is turned upwardly against the tension of the spring 16 until the notch 37 registers with the perforation 38. Then the pin 39 may be inserted through 30 said perforation and notch to rigidly hold the hanger in line with the clamp as shown in Fig. 2. When in this position the press may be readily connected to the hanger by the internally threaded nipple 40 formed in 35 one end of the press casing which may be attached either to the screw thread upon the nipple 21 of the hanger 14 or upon a similar threaded pin 43 at the end of the handle D. When the press is used in connection with 40 the rack A it is important to be observed that the threaded pintle 21 and nipple 40 are not to be turned into locking position, because the press must be left free to swivel on the nipple 21 so as to allow transverse 45 play of the press when, as is frequently the case, the roll of paper on which the printing is to be done is irregularly rolled or for other reasons presents an uneven surface to the printing roller 25.

50 After attaching the press C to the hanger 14 as above described the pin 39 is withdrawn from the perforation 38 and notch 37 to permit the printing roller 25 of the press to rest upon the surface 42 of the paper upon 55 the rack A. The type of the printing roller is held in operative position upon the paper both by gravity and the tension of the spring 16, and transverse irregularities in the paper roll are compensated for by the swiveling 60 of the nipple 40 upon the threaded pintle 21.

When my printing-device is adjusted upon the wrapping paper rack as shown in Fig. 1

the movement of the wrapping paper as it is unrolled by the attendant rotates the printing roller 25, causing the inked type thereon 65 to press upon the surface of the paper and imprint the text carried by said roll upon the surface of such paper, it being understood that during this operation the detent 31 is in the position shown in Fig. 6, to permit continuous rotation of the printing roller 25 in one direction.

When the handle D is attached to the press for manual operation the detent 31 must be adjusted to the position shown in 75 Fig. 5, and the printing roller is then rolled across the surface of the paper or other article to be printed, after which the roller is lifted from paper and permitted to return to the initial position by the action of the 80 spring 27.

Having described my invention, what I claim as new and desire to protect by Letters Patent, is:

1. In a printing device of the class described a clamp adapted to be mounted upon a roll-paper rack, a hanger pivotally suspended on said clamp, a press swiveled on said hanger to permit transverse play on a paper roll, a spring between said hanger and clamp adapted to hold said press against the paper roll and means for rigidly connecting said hanger with said clamp. 85

2. In a printing device of the class described a clamp adapted to be secured to a roll-paper rack, a hanger pivotally mounted in said clamp, a printing press suspended from said hanger, a spring interposed between the clamp and hanger and adapted to hold said press against a paper roll and a swiveled joint comprising loosely united threaded members, connecting the press with the hanger to permit transverse play of said press on the roll of paper. 95

3. In a printing device of the class described, a casing, a train of rollers mounted and rotatable in said casing in serial, peripheral contact with each other, one of said rollers being formed with a cavity in its end, a disk in said cavity loosely mounted 110 to revolve on the same axis with said roller, a coil spring also in said cavity attached at one end to said roller and at the other end to said disk, and a spring controlled detent mounted in the casing and adapted to engage 115 said disk and hold the same against rotation.

In testimony whereof, I have signed my name to this specification in the presence of two subscribing witnesses.

SHERMAN H. PAXTON.
